(57) **CLAIM**

The ornamental design for an articulated truck, as shown and described.

DESCRIPTION

This patent or application filed contains at least one drawing executed in color. Copies of this patent or patent application publication with color drawings will be provided by the Office upon request and payment of the necessary fee.

FIG. 1 is a right front perspective view of an articulated truck according to one aspect of the present design;

FIG. 2 is a left front perspective view of the articulated truck design of FIG. 1;

FIG. 3 is a left side perspective view of the articulated truck design of FIGS. 1 and 2;

FIG. 4 is a right perspective view of the articulated truck design of FIGS. 1-3; and,

FIG. 5 is a top view of the articulated truck design of FIGS. 1-4.

The stippled portions of the Figures are included to show visible environmental structure and are not portions of the design. Color, namely black and yellow, are an aspect of the design.
